US0D1071218S

(12) **United States Design Patent** (10) **Patent No.:** **US D1,071,218 S**
(45) **Date of Patent:** **** Apr. 15, 2025**

(54) **MEDICAL CANNULA**

(71) Applicants: **YURIM MEDICAL Co., Ltd.**,
Cheongju-si (KR); **Woo Ram KIM**,
Cheongju-si (KR)

(72) Inventors: **Hae June Yahng**, Cheongju-si (KR);
Woo Ram Kim, Cheongju-si (KR)

(73) Assignees: **YURIM MEDICAL Co., Ltd.**,
Cheongju-si (KR); **Woo Ram Kim**,
Cheongju-si (KR)

(**) Term: **15 Years**

(21) Appl. No.: **29/893,122**

(22) Filed: **May 25, 2023**

(30) **Foreign Application Priority Data**

Jan. 12, 2023 (KR) 30-2023-0001470

(57) **CLAIM**

The ornamental design of a medical cannula, as shown and described.

DESCRIPTION

FIG. 1 is a perspective view of a medical cannula showing the claimed design;

FIG. 2 is a front view thereof;

FIG. 3 is a rear view thereof;

FIG. 4 is a left side view thereof;

FIG. 5 is a right side view thereof;

FIG. 6 is a top plan view thereof; and,

FIG. 7 is a bottom plan view thereof.

The broken lines form no part of the claimed design.

1 Claim, 4 Drawing Sheets
